UNITED STATES PATENT OFFICE.

FREDERICK K. MAERZ, OF CLEVELAND, OHIO.

DESIGN FOR AN ELECTRIC-LIGHTING FIXTURE.

Application filed September 8, 1924. Serial No. 10,710. Term of patent 3½ years.

To all whom it may concern:

Be it known that I, FREDERICK K. MAERZ, a citizen of the United States, residing at Cleveland, in the county of Cuyahoga and State of Ohio, have invented a new, original, and ornamental Design for Electric-Lighting Fixtures, of which the following is a specification, reference being had to the accompanying drawing, forming part hereof, wherein—

Fig. 1 is a side elevation and Fig. 2 a front elevation of a fixture exhibiting my new design.

I claim:

The ornamental design for an electric lighting fixture as shown.

FREDERICK K. MAERZ.
